UNITED STATES PATENT OFFICE.

FREDERICK MULLER, OF ELIZABETH, NEW JERSEY.

HOLDER FOR SINE-BARS AND SIMILAR IMPLEMENTS.

Specification of Letters Patent. Patented Feb. 27, 1917.

1,217,487.

Application filed August 4, 1916. Serial No. 113,188.

To all whom it may concern:

Be it known that I, FREDERICK MULLER, a citizen of the United States, and a resident of Elizabeth, in Union county and State of New Jersey, have invented certain new and useful Improvements in Holders for Sine-Bars and Similar Implements, of which the following is a specification.

This invention relates to a holder of novel construction by means of which sine bars, indicator bars, scribe bars and similar delicate implements may be adjusted with great accuracy. The holder is so constituted that the sine bar or other implement carried thereby may first be moved into close proximity to the work piece and may then be tilted to conform to the dip thereof, the several operations being performed in the most accurate manner. The invention consists in the various features of construction more fully pointed out in the specification and appended claims.

In the accompanying drawing:

Figure 1 is a rear elevation of a holder embodying my invention and showing it used as a support for a sine bar;

Fig. 2, a side view;

Fig. 3, a section on line 3-3, Fig. 1;

Fig. 4, a section on line 4-4 Fig. 1;

Fig. 5, a plan partly in section of the base and square;

Fig. 6 a section on line 6-6 Fig. 2;

Fig. 7, a section on line 7-7 Fig. 1;

Fig. 8 a vertical section through the slide

adjusting means;

Fig. 9, a section on line 9-9, Fig. 1, and

Fig. 10 a diagram showing the sine bar lowered against a base plate.

To a suitable base 1 are secured by means of bushings 2 or otherwise, a pair of upright parallel guide rods 3. Along these rods is adapted to travel, vertically, a slide 4 coöperating with a clamp 5, said parts being grooved at their contiguous inner faces to grasp rods 3 (Fig. 3). Means are provided to accurately set the slide vertically, and also to clamp the same to the rods after being set. These means are as follows:

Into slide 4 is tapped a screw 6 having a tubular barrel 7 passing loosely through clamp 5 and encompassed by a spring 8. The rear threaded end of barrel 7 carries a jam nut 9 that engages the rear face of clamp 5. By slackening the nut, spring 8 will

cause the hold of the slide 4 and clamp 5 on rods 3 to be relaxed, so that the slide may be moved up or down along the rods. When the nut is tightened up, it will crowd the parts 4, 5 against the rods, so that the slide will become clamped to the latter. 60

Through barrel 7, passes axially, a pin 10 the rear threaded end of which projects beyond the barrel and carries a jam nut 11, adapted to engage the end of the barrel. The inner or forward end of pin 10 carries a split tubular jaw 12 that engages a vertical bar 13 centered between rods 3. This bar is vertically movable, its lower end being stepped loosely into a bushing 14 of base 1. The upper threaded end of bar 13 is engaged by the threaded bushing 15 of a tubular set screw 16, that bears upon a cross piece 17 mounted upon the upper ends of rods 3. 70

In order to vertically adjust slide 4, nut 75 9 is slackened, and nut 11 is tightened up so as to clamp pin 10 (and consequently slide 4) to rod 13. By now manipulating set screw 16 rod 13 will be raised or lowered axially to correspondingly raise or lower 80 the slide. After the adjustment desired has been attained, the slide is locked in position by tightening nut 9.

Slide 4 is provided with a horizontal bore within which is accommodated, an axially rotatable horizontal tubular sleeve 18, which is of a length to protrude from both ends of the slide. This sleeve contains a rotatably and axially movable spindle 19, which carries the implement to be set by means of the 90 holder. With the embodiment shown, the forward end of the spindle is furnished with a socketed member or tool head 20 having a transverse aperture that receives an axially slideable sine bar 21 having bulged 95 ends 22. This bar is adapted to be held-frictionally in position by means of a plunger 23, housed within socketed member 20, and projected against the bar by means of a spring 24. A rough adjustment of the spindle 19, may be effected by manually turning the same within sleeve 18, whereby the dip of the sine bar 21 may be made to approximate the inclination of the work piece, while a previous axial movement of the spindle 100 within the sleeve, will have caused the sine bar to have been projected over the work piece. After this rough adjustment has been 105

effected, spindle 19 may be locked to the sleeve by means of a clamp screw 25 engaging a threaded stud 26 projecting through the sleeve and having a split tubular jaw 27 that engages the spindle.

Upon the rearwardly protruding end of sleeve 18, is mounted a worm wheel 28 engaged by a worm 29 mounted in a bearing 30 of slide 4. By turning this worm, a corresponding axial rotation will be imparted to sleeve 18, so that the latter may be delicately adjusted and impart a corresponding delicate adjustment to the spindle and consequently to the sine bar. After the sleeve has thus been set, it may be locked against displacement by means of a spring influenced clamp screw 31 engaging a threaded stud 32 which extends upwardly from a clamp jaw 33. This jaw is received within a transverse slot of slide 4, and is apertured as at 34, so as to encompass sleeve 18. When screw 31 is tightened, it will by bearing upon a washer 35, supported on slide 4, draw jaw 33 slightly upward so that sleeve 18 becomes tightened within the bore of the slide.

In order to set the work piece, to the sine bar or other implement, base 1, is provided with two intersecting horizontal bores, extending therethrough at right angles. Either one of these bores is adapted to receive the spindle 36 of a gage or flat stock 37 which may be locked in position by means of a clamp screw 38 (Fig. 9) adapted to bear upon a washer 39, mounted on base 1. Screw 38 engages threaded stud 40 of a split tubular jaw 41 that grasps spindle 36, at the intersection of the bores. By providing the base with the two bores as described, either side of a work piece may be properly gaged.

The operation of the holder will be apparent from the foregoing description. After the work piece has been set up along-
45 side of the holder, slide 4 is moved by set screw 16 to such an elevation as to bring the implement 21 to a plane somewhat above the work piece. Spindle 19 is pushed out to carry the implement above the work piece,
50 and is manually turned so that the implement assumes approximately the dip or angle desired, the fine adjustment being attained after the spindle has been locked to sleeve 18 by manipulating worm 29.

55 In case of a sine bar, the slide is then lowered, carrying the sine bar into the position shown in Fig. 10, and against a base or bench 42. The distance of the nearest point of upper ball 22 to said bench is measured, that distance is divided by the given dis-
60 tance between the centers of balls 22, and the quantity thus obtained will be the sine of the angle. By referring to the sine table, the angle itself may now be found accurate
65 to a minute.

I claim:

1. A holder of the character described, comprising a base, a pair of rods extending upwardly therefrom, a slide movable along the rods, a clamp carried by the slide and adapted to lock the same to said rods, a bar intermediate the rods, means for moving said bar vertically, means for locking the slide to said bar, and an implement holding member carried by the slide.

75 2. A holder of the character described, comprising a base, a pair of rods extending upwardly therefrom, a slide and a coacting clamp engaging the rods, a vertically movable bar having an upper threaded end, 80 means for locking the slide to said bar, a set screw engaging the bar, a cross piece carried by the rods and engaged by the set screw, and an implement holding member carried by the slide.

85 3. A holder of the character described, comprising a base, a pair of rods extending upwardly therefrom, a slide and a coacting clamp engaging the rods, a threaded tubular barrel carried by the slide, a nut threaded 90 on said barrel and adapted to engage the clamp, a threaded spindle within the barrel, a nut threaded on said spindle and adapted to engage the barrel, a jaw carried by the spindle, a bar engaged by the jaw, means 95 for moving said bar vertically, and an implement holding member carried by the slide.

100 4. A holder of the character described, comprising a base, a pair of rods extending upwardly therefrom, a slide and a coacting clamp engaging the rods, a threaded tubular barrel carried by the slide, a nut threaded on said barrel and adapted to engage the clamp, a threaded spindle within the barrel, 105 a nut threaded on said spindle and adapted to engage the barrel, a jaw carried by the spindle, a vertically movable bar having an upper threaded end and engaged by the jaw, a set screw engaging the bar, a cross piece 110 carried by the rods and engaged by the set screw, and an implement holding member carried by the slide.

115 5. A holder of the character described, comprising a base, a member projecting upwardly therefrom, a slide engaging said member, a tubular sleeve rotatably mounted within the slide, a worm wheel on the sleeve, a worm carried by the slide and engaging the worm wheel, a rotatable and axially 120 movable spindle within the sleeve, and means for locking said spindle to said sleeve.

125 6. A holder of the character described, comprising a base, a member, projecting upwardly therefrom, a slide engaging said member, a tubular sleeve rotatably mounted within the slide, a worm wheel on the sleeve, a worm carried by the slide and engaging the worm wheel, an apertured clamp jaw mounted in the slide and engaging the 130

sleeve, a threaded stud projecting from the jaw, a clamp screw engaging the stud, a spindle rotatable within the sleeve, and means for locking said spindle to said sleeve.

5 7. A holder of the character described, comprising a base, a pair of rods extending upwardly therefrom, a slide engaging the rods, a clamp adapted to lock the slide to the rods, a bar interposed between the rods,

means for locking the slide to said bar, 10 means for imparting an axial movement to the bar, a sleeve rotatable within the slide, a worm wheel carried by the sleeve, a co-acting worm carried by the slide, a rotatable spindle within the sleeve, and means for 15 locking the spindle to said sleeve.

FREDERICK MULLER.
